OIL REGULATING MEANS FOR SEWING MACHINES

David A. Graesser, Elizabeth, N. J., assignor to
The Singer Manufacturing Company, Elizabeth,
N. J., a corporation of New Jersey

Application January 5, 1940, Serial No. 312,467

6 Claims. (Cl. 112—256)

This invention relates to sewing machines and more particularly to means for supplying oil to the raceway of a rotary hook, and has for its objective the provision of improved means for regulating the flow of oil to the raceway of the hook.

The supply of oil to the raceway of a rotary hook must be very accurately controlled. Too much oil will soil the material being sewn and too little will cause the hook to heat and destroy the bearing surface of the raceway. Heretofore means have been provided for regulating the flow of oil to the raceway of a hook. However, in these prior devices, if the regulating means should become clogged, the oil supply to the raceway of the hook ceases and the hook is quickly destroyed by friction and heat. It is one of the objects of my invention to overcome this difficulty.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the drawing—

Figure 1 is a vertical section taken through the bed of a sewing machine embodying my invention, the operating parts below the bed being shown in full lines.

Figure 2 is a sectional view taken along the line 2—2 of Figure 3.

Figure 3 is an end elevation, looking from the right of Figure 2.

Figure 4 is a fragmentary detail view.

Figure 5 is a view similar to Figure 2, of a modified form of my improved device.

In the embodiment of this invention selected for illustration, 10 represents the bed-plate of a machine formed with depending side and end walls which rest upon the gasket of resilient material 11 carried by the oil-pan 12. The bed 10 of the sewing machine together with the oil-pan form an oil-tight compartment which houses the actuating mechanism of the machine.

Carried by the bed 10 of the machine is a centrifugal pump 13, actuated by the usual vertical shaft 14 which has its upper end operatively connected to the needle-bar actuating shaft (not shown). The shaft 14 through the gears 15 and 16 actuate the hook-shaft 17 which is journaled in the bearing bushings 20, 21 carried

by the bed. Fixed to the end of the shaft 17 is a rotary hook 18 which cooperates with the usual reciprocating needle 19 in the formation of lock-stitches. For a more detailed description of the sewing machine oil-pan and oil-pump reference may be had to Patent No. 2,206,285 dated July 2, 1940, issued to R. Kaier for a Sewing machine.

As more clearly shown in Figs. 2 and 5, the bearing bushing 20 is formed with a conduit 22 which is connected with the centrifugal pump 13 by the tube 23 so that when the machine is operating oil is supplied from the reservoir A by the centrifugal pump 13 through the tube 23 and to the conduit 22 under pressure. Conduit 22 communicates with an internal circular groove 24 which is formed in the bushing and supplies oil to the bearing surface between the bearing bushing 20 and the shaft 17, the shaft 17 being provided with a spiral groove 25 which returns the oil to the reservoir. The bearing bushing is also formed with a conduit 26 which is arranged below the level of the hook-shaft 17 (Fig. 3) and connects the circular groove 24 with a second circular groove 28 which is formed slightly eccentric relative to the shaft 17 so that its outer periphery will connect with the conduit 26 but will not connect with the conduit 22.

The shaft 17 is formed with a longitudinal arranged bore 30 and a radial duct 31 which communicates with the circular groove 28 in the bearing bushing 20. The end of the hook-shaft 17, to which the hook 18 is fixed is provided with a screw 32 which closes the open end of the longitudinal bore 30 in the shaft 17. Carried by the screw and extending into the bore 30 is a filter cartridge 34 for filtering oil passing through it and the cartridge may be readily removed, cleaned, and replaced or if desired a new filter may be substituted for the old one.

The screw 32 is formed with a radial duct 36 which leads the oil, that passes through the filter 34, to a circular chamber 37 formed between the screw 32 and the hook-shaft. The oil is led from the chamber 37 through a radial duct 38 and circumferential groove 38' in the shaft 17 to the conduits 39 formed in the body of the hook 18. These conduits 39 are disposed substantially 180° apart and the outer ends are connected with the raceway 40 formed in the hook-body by the grooves 41. Journaled in the raceway 40 in the hook-body is the bearing rib 42 of the usual stationary thread-case 43. It will be understood that the thread-case is formed with an ear 44 which cooperates with a thread-case restraining finger fixed to a stationary part of

the machine, for the purpose of preventing the thread-case from turning with the rotary hook.

The pump and conduits are designed to supply an excess of oil to the conduit 26 so that if the open end of the conduit 26 is completely closed an excess of oil will be supplied to the raceway of the hook, and if the end of the conduit 26 is wide open no oil will be supplied to the hook. In order to regulate the flow of oil to the hook, I have provided a disk 44 which is fitted on the end of the bushing 20 which extends into the reservoir. The disk 44 is formed with an elongated slot 45 through which the oil supply tube 23 extends. The disk 44 is also formed with a second elongated slot 46 which receives the shouldered screw 47 threaded into the bushing 20, this slot being adapted to overlie the end of the conduit 26. Between the head of the screw 47 and the disk 44 there is interposed a flat spring 48 which resiliently urges the disk against the bushing and frictionally holds it in adjusted position. To adjust the flow of oil to the hook raceway, it is only necessary to grasp the finger-piece 49 and shift the disk in the direction desired. It will, of course, be understood that one end of the slot 46 is so arranged that shifting of the disk in a clockwise direction as viewed in Figure 3 will close the end of the conduit 26 and shifting the disk 44 in a counterclockwise direction will open the conduit.

In Figure 5 I have shown a modification of my improved oil regulating device. In this modification a plug 50 is screwed into the open end of the conduit 26. The plug 50 is formed with a centrally arranged longitudinal bore 51 and radial ports 52. A screw 53 having a tapered end is threaded into the longitudinal bore of the plug 50 so that it may be adjusted longitudinally to regulate the flow of oil out of the ports 52, and a lock-nut 55 is provided for the purpose of locking the screw 53 in its adjusted position.

From the above it will be understood that if for any reason the reduced openings to the ports 52, or the reduced opening shown in Figure 3, become clogged the pressure of the oil in the conduit 26 will increase and the oil will be supplied to the hook in too large a quantity. When this is noticed by the operator it will only be necessary to shift the disk 44, or back out the screw 53 and clean the openings.

From the foregoing description it will be obvious that the elements employed and details of construction are susceptible of material variations. The privilege is therefore reserved of resorting to all such legitimate changes therein as may be fairly embodied within the spirit and scope of the appended claims.

Having thus set forth the nature of the invention, what I claim herein is:

1. A sewing machine having in combination, a rotatable hook-shaft formed with a longitudinal bore, a hook carried by said shaft and having a raceway in which a thread-case is journaled, oil conducting means for conducting oil from the bore of said shaft to the raceway in said hook, a conduit for supplying oil to the bore in said shaft, an oil reservoir, means for supplying oil under pressure from said reservoir to said conduit, and adjustable means connected with said conduit for allowing some of the oil in the conduit to return to said reservoir.

2. A sewing machine having in combination, a rotatable hook-shaft formed with a longitudinal bore, a hook carried by said shaft and having a raceway in which a thread-case is journaled, oil conducting means for conducting oil from the bore of said shaft to the raceway in said hook, a conduit for supplying oil to the bore in said shaft, a bushing in which the hook-shaft is journaled, said bushing being formed with a conduit which communicates with the bore in said shaft, means for supplying oil under pressure to said conduit, and means associated with said conduit for regulating the pressure of the oil therein.

3. A sewing machine having in combination, a rotatable hook-shaft formed with a longitudinal bore, a hook carried by said shaft and having a raceway in which a thread-case is journaled, oil conducting means for conducting oil from the bore of said shaft to the raceway in said hook, a conduit for supplying oil to the bore in said shaft, a bushing in which said hook-shaft is journaled, said bushing being formed with a conduit which communicates with the bore in the hook-shaft, an oil reservoir below the level of said shaft, a pump for supplying oil under pressure from said reservoir to the conduit, means for returning some of the oil supplied to said conduit to said reservoir and means for regulating the amount of oil returned to the reservoir.

4. A sewing machine having in combination, a rotatable hook-shaft formed with a longitudinal bore, a hook carried by said shaft and having a raceway in which a thread-case is journaled, oil-conducting means for conducting oil from the bore of said shaft to the raceway in said hook, a conduit for supplying oil to the bore in said shaft, a bushing in which said hook-shaft is journaled, said bushing being formed with a conduit which communicates with the bore in the hook-shaft, an oil reservoir below the level of said shaft, a pump for supplying oil under pressure from said reservoir to the conduit, means for returning some of the oil supplied to said conduit to said reservoir and manually controlled means for regulating the amount of oil returned to the reservoir.

5. A sewing machine having in combination, a rotary hook provided with a bearing raceway, an oil reservoir, a conduit leading to the raceway in said hook, a pump for supplying oil under pressure from said reservoir to said conduit, means for conducting some of the oil in said conduit back to the reservoir, and adjustable means for regulating the amount of oil returned to the reservoir.

6. A sewing machine having in combination, a hook-shaft provided with a longitudinal bore, a hook secured to said shaft and provided with a raceway which communicates with the bore in said shaft, a radially arranged duct leading to the bore in said shaft, a filter located in the bore of said shaft, a bushing provided with a conduit which communicates with the radial duct in the shaft, a reservoir located below said bushing, means for supplying oil from the reservoir to the conduit in the bushing under pressure, and an adjustable valve located in the conduit in said bushing for regulating the pressure of the oil in said conduit.

DAVID A. GRAESSER.
